UNITED STATES PATENT OFFICE

JACQUES FRANKL, OF VIENNA, AUSTRIA

CLOTHES TRUNK

Application filed January 7, 1932, Serial No. 585,350, and in France October 20, 1931.

This invention relates to a novel clothes trunk for a large number of articles of clothing, which is considerably shorter in the closed condition than the full length of the clothes placed therein, and which can therefore easily be stowed in a railway train compartment or the like. In accordance with the invention the trunk can be transformed by a few simple operations into a hanging stand for the clothes. The trunk is thus particularly suitable for actors, commercial travellers, and others, and also for exhibition purposes.

Within the trunk there is arranged, in accordance with the invention, a two-part framework, in such a manner that the same is pivotally attached to the side of the trunk opposite the opened lid. On the upper part of this framework there is arranged a rail 20 for the hanging of clothes hooks or carriers, a collapsible rod being provided for the extension or elongation of this rail. When the trunk is in the opened-out condition, this rod can be attached horizontally to a sliding support housed in the lid of the trunk, so as to provide a hanging stand on which the clothes carried in the trunk can be hung in their full length to be kept in readiness for wearing, or for show purposes.

30 The pivot about which the parts of the framework are arranged to turn is so constructed that the clothes cannot become pinched or jamb at the side when the framework is folded up, and the appearance 35 of transverse creases due to the folding of the clothes is also effectually prevented by the special features of the construction of this part of the trunk.

One form of the invention is illustrated, 40 by way of example, in the accompanying drawings, in which:—

Fig. 1 shows the trunk, open, in perspective.

Fig. 2 shows the trunk in the act of being 45 opened or closed, likewise in perspective.

Fig. 3 is a longitudinal section of the closed trunk.

Fig. 4 is a plan view of the open trunk.

Figs. 5 and 6 are sections taken on the lines 50 V—V and VI—VI, respectively, of Fig. 4.

Fig. 7 is a section taken on the line VII—VII of Fig. 5.

Referring to the drawings, the trunk 1 is provided with a lid 2 which can be fixed in an upright position at right angles to the body of the trunk by means of props 3. At the opposite side of the trunk to the open lid there is pivotally mounted upon pins 6 a two-part foldable framework 4, 5. The two parts 4 and 5 of this framework are connected together by means of hinges 7; the axle 8 about which the two parts of the framework can be folded together in the manner indicated by the arrow Y is provided with end discs 10 and with a freely rotatable encasing sleeve 9, for the purpose of preventing the pinching of the clothes at the side or the rubbing of the axle against the clothes during the opening-out and folding-up of the framework 4, 5. To the inner face of the upper wall of the framework there is attached the rail 11 which is of hook-shaped cross-section to enable the clothes-hangers 12 to be hung thereon. These hangers can be slid easily along the rail. The lower portion 4 of the framework is provided with locking means 16 for holding the same in the upright position at right angles to the body of the trunk. To the rail 11 there is articulated a rod 13 the free outer end of which can be fitted into an aperture 15 in the support 14 which is housed within and adapted to be withdrawn from the lid 2 of the trunk. After the freeing of a locking device 26, the hangers 12 can be slid across from the rail 11 on to the rod 13. On the portions 4 and 5 of the framework there are arranged movable flaps 17 and 18 which are drawn outwards by means of elastic bands 19. To these flaps there are pivotally attached straps 20 or the like which are connected together by suitable means, e. g. snap fasteners 21, and when joined serve to hold the clothes in position for closing the trunk. For the purpose of retaining the parts 4 and 5 of the foldable framework in the extended condition, bridging pieces 23 are provided on the ends of the side flaps of one of the parts of the framework to overlap the abutting ends of the side flaps of the other part, snap 100

fasteners being provided the one portion 22 of which is attached to the side flaps overlapped by the bridging pieces 23, while the counter portion 24 is suitably attached to the 5 under side of the bridging pieces.

When the trunk is to be closed, all the clothes are first slid with their hangers into the framework, and the locking device 26 is closed. The rod 13 is then withdrawn 10 from the aperture 15 in the support 14 and folded down. The support 14 is then liberated from a retaining spring 25 and slid back into the lid 2. The clothes are then fixed in position in the framework 4, 5 by means of 15 the side flaps 17 and 18 and of the straps 20, after which the two parts of the framework 4 and 5 are folded together as indicated by the arrow Y, whereby the clothes are folded in a body, i. e. without the formation 20 of sharp transverse creases, around the sleeve 9. By the provision of the end plates 10 on the axle 8 the pinching of the clothes at the side is prevented, and by the provision of the freely rotatable sleeve 9 the rubbing of the 25 clothes against the axle 8 is likewise effectually prevented. The folded framework is then swung into the trunk as indicated by the arrow Z, after which the trunk is closed. To open the trunk the same procedure is 30 gone through in the reverse order of the individual operations.

I claim:—

1. A clothes trunk comprising in combination with a body portion a lid hinged to 35 one side of the said portion, corner props for holding the lid in a position at right angles to the said body portion, a two-part framework pivotally attached to the side of the said body portion opposite the said lid, 40 and a hinge comprising a hinge axle between the two parts of the said framework for the purpose of enabling the said two parts to be folded together and to lie one upon the other within the trunk when the latter is in the 45 closed condition, and further comprising a rail for the suspension of clothes hangers attached to the end portion of the said two-part framework farthest removed from the 50 said body portion of the trunk when in the open condition, an extension rod articulated to the said rail, an extensible support housed within the said lid, and an aperture in the 55 said support adapted to be engaged by the end of the said extension rod when the said rod is substantially parallel to the base of the trunk.

2. A clothes trunk as claimed in claim 1, further comprising a freely rotatable sleeve fitted over and adapted to encase the said hinge axle, and plates attached to the ends 60 of the said axle.

3. A clothes trunk as claimed in claim 1, further comprising side flaps movably attached to the lateral edges of the said framework facing the open lid of the trunk, elas- 65

tic bands adapted to draw the said flaps outwards, straps or the like articulated to the said flaps, and means for joining together the said flaps, for the purpose of holding clothes in position within the said frame- 70 work.

In testimony whereof I affix my signature.
JACQUES FRANKL.
